(57) **CLAIM**

The ornamental design for a cutting head as shown and described.

DESCRIPTION

FIG. 1 is a top, front and right side perspective view of a cutting head showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 2.

(Continued)

The uniform dash broken lines shown in the drawings represent portions of the cutting head that form no part of the claimed design.

The dash-dot-dash broken lines define the enlargement regions and form no part of the claimed design.
